UNITED STATES PATENT OFFICE

165,927

CIGARETTE LIGHTER

Pierre E. Mora, Geneva, Switzerland, assignor to
Perhi, S. A., Geneva, Switzerland

Application June 20, 1951, Serial No. 15,615
In Switzerland (International Application)
February 9, 1951

Term of patent 7 years

(Cl. D48—27)

To all whom it may concern:

Be it known that I, Pierre E. Mora, citizen of Italy, residing at Geneva, Canton of Geneva, Confederation of Switzerland, have invented a new, original, and ornamental Design for Cigarette Lighter, of which the following is a specification, reference being had to the accompanying drawing, forming part thereof:

Fig. 1 is a front elevational view of a cigarette lighter, showing my new design;

Fig. 2 is a side elevational view;

Fig. 3 is a top plan view; and

Fig. 4 is a perspective view thereof.

I claim:

The ornamental design for a cigarette lighter, as shown.

PIERRE E. MORA.
